INVENTOR:

G. F. Murphy,
by A. Z. Vencell
His Attorney

UNITED STATES PATENT OFFICE.

GEORGE F. MURPHY, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SKATE-OPERATING APPARATUS.

Application filed July 21, 1927. Serial No. 207,438.

My invention relates to railway skate operating apparatus, that is, apparatus for moving a track skate to and from its active position on the track rail.

5 My present invention is an improvement on the apparatus shown in application for Letters Patent of the United States, filed by Edwin G. Little on January 26, 1926, Serial No. 83,912, for railway skate operating apparatus, which application has matured into Patent No. 1,641,178, dated September 6, 1927.

10 I will describe one form of skate operating apparatus embodying my invention, and 15 will then point out the novel features thereof in claims.

15 In the accompanying drawing, Fig. 1 is a view, partly in side elevation and partly in vertical section, showing one form of skate 20 operating apparatus embodying my invention. Fig. 2 is a top plan view showing the cradle 11 and arms 5 and 5^a forming part of the apparatus shown in Fig. 1. Fig. 3 is a 25 view, showing in side elevation, the parts of the apparatus illustrated in Fig. 2.

Similar reference characters refer to similar parts in each of the several views.

Referring first to Fig. 1, the reference character A designates a track rail of a rail-way track, and the reference character B 30 designates a skate which is to be moved to and from its active position on the tread of the rail A.

Located in the trackway beside the rail A, 35 is a housing 7 in which a link 8 is pivotally suspended from a shaft 9. The lower end of the link 8 is forked, and the two prongs in the fork are provided with holes to receive a shaft 10. The shaft 10 passes freely 40 through two lugs 11^a formed on a cradle 11, so that this cradle is free to swing around the shaft 10 as a center. The right-hand end of the cradle 11 carries a roller 12, which rolls on a fixed cam 14 supported within the housing 7. The shaft 10 also passes freely 45 through holes in two spaced lugs 15, 15, projecting from an arm 5, and through two spaced lugs 15^a, 15^a, projecting from an arm 5^a, so that these arms are pivotally 50 mounted on the shaft. The arms 5 and 5^a normally rest on the top of the cradle 11, and a screw 2 projects downwardly from each arm and engages a surface 3 on the top

of the cradle 11, so that the normal position of the arm with respect to the cradle can be 55 adjusted by turning the screw. Each screw is locked in adjusted position by a nut 4. The two forks on the lower end of link 8 lie in the space between lugs 15^a and 11^a, and in the space between lugs 11^a and 15, respectively. 60

The arms 5 and 5^a are provided with aligned yokes 13 to detachably receive a single straight lug 6 on the skate B. As here shown, each jaw of each yoke is provided 65 with a central rib 13^a, and the jaw flares outwardly from this rib to provide considerable clearance between the jaws and the lug 6 at the outer edges of the yoke.

The link 8 is pivotally connected with an 70 operating rod 17 which may be moved longitudinally by any suitable means, such, for example, as the motor device D shown in the application by Edwin G. Little identified above. 75

When the operating rod 17 is in its retracted position, the parts occupy their normal positions in which they are shown in the drawing, and the skate B is retracted from the track rail A. If now the rod 17 is projected toward the right, link 8 will be swung in counter-clockwise direction, thereby moving the cradle 11 and the arms 5 and 5^a to the right as viewed in Fig. 1, with the result that the skate B is lifted over the track rail 80 A and is dropped into active position on the tread of the rail. When the rod 17 is again retracted, the skate B will again be lifted clear of the rail A and then will be returned to its retracted position in which it is shown 85 in the drawing. 90

I have found that when a car wheel rides upon the skate A, the skate is some times tipped or rocked longitudinally to a sufficient extent to break either the lug 6 or the 95 yoke which engages this lug. In apparatus embodying my invention, when this tipping motion of the skate occurs, one of the arms 5 or 5^a will be swung upwardly around the shaft 10 as a center, and the lug 6 will roll 100 in the flared jaws 13, thereby avoiding any undue strain on either the lug 6 or the jaws 13.

Although I have herein shown and described only one form of skate operating 105 apparatus embodying my invention, it is un-

derstood that various changes and modifications may be made therein within the scope of the appended claims without departing from the spirit and scope of my invention.

3. Having thus described my invention, what I claim is:

1. A railway skate operating mechanism comprising a cradle, two arms pivotally connected with said cradle and normally resting thereon, said arms having aligned yokes for detachably engaging a skate, and means for moving said cradle to shift the skate to and from its active position on the track rail.
10. 2. A railway skate operating mechanism comprising a cradle, two arms pivotally connected with said cradle and normally resting thereon, said arms having aligned yokes for detachably engaging a skate, and means for moving said cradle to shift the skate to and from its active position on the track rail.
15. 3. A railway skate operating mechanism comprising a cradle, two arms pivotally connected with said cradle and normally resting thereon, said arms having aligned yokes for detachably engaging a skate, and means for moving said cradle to shift the skate to and from its active position on the track rail, each jaw of each yoke being flared outwardly from a central line which is normally engaged by the skate.
20. 4. A railway skate operating mechanism comprising a cradle, two arms pivotally connected with said cradle and normally resting thereon, said arms having aligned yokes for detachably engaging a skate, and means for moving said cradle to shift the skate to and from its active position on the track rail.
25. 5. A railway skate operating mechanism comprising a cradle, two arms pivotally connected with said cradle and normally resting thereon, said arms having aligned yokes for detachably engaging a skate, and means for moving said cradle to shift the skate to and from its active position on the track rail.

ing thereon, means for adjusting the normal position of each arm with respect to said cradle, said arms having aligned yokes for detachably engaging a skate, and means for moving said cradle to shift the skate to and from its active position on the track rail.

4. A railway skate operating mechanism comprising a cradle, a shaft passing through said cradle, two arms pivotally supported on said shaft and normally resting on said cradle, said arms having aligned yokes to detachably engage a single straight lug on the skate, and means for moving said cradle to shift the skate to and from its active position on the track rail.

5. A railway skate operating mechanism comprising a cradle, two arms pivotally connected with said cradle and normally resting thereon, said arms having aligned yokes with flaring jaws for detachably engaging a skate, and means for moving said cradle to shift the skate to and from its active position on the track rail.

In testimony whereof I affix my signature.

GEORGE F. MURPHY.
